United States Patent Office

Des. 180,566
Patented July 2, 1957

180,566

CABINETED POWDER DISPENSER

Marc H. Sessions, Los Angeles, Calif., assignor to United States Borax & Chemical Corporation, Los Angeles, Calif., a corporation of Nevada

Application July 19, 1956, Serial No. 42,296

Term of patent 14 years

(Cl. D4—3)

FIG. 1.

FIG. 2.

Fig. 1 is a front perspective view of a cabineted powder dispenser, showing my new design; and

Fig. 2 is a rear perspective view thereof.

I claim:

The ornamental design for a cabineted powder dispenser, as shown.
